TELEVISION APPARATUS

Melchor Centeno V., Caracas, Venezuela, assignor
to International Television Radio Corporation,
New York, N. Y.

Application August 4, 1932, Serial No. 627,519

9 Claims. (Cl. 178—6)

This invention relates to television apparatus. One of the objects of the present invention is

to provide a novel system of television transmission and reception, including novel means for 5 securing exact synchronism of the scanners.

Another object is to provide a novel system of stereoscopic television.

A further object is to provide an improved and simple form of scanner.

10 Still another object is to provide novel means for accomplishing direct television.

Another object is to provide means whereby compactness of apparatus is secured.

15 Still another object is to provide means for obtaining uniformity of light on the scanning area.

Other objects and advantages of the invention will be pointed out or will become apparent as the specification proceeds.

20 The invention will be fully and comprehensively understood from a consideration of the following detailed description when read in connection with the accompanying drawings which form part of the application with the understand-

25 ing, however, that the improvement is capable of extended application and is not confined to the exact showing of the drawings nor to the precise construction described, and, therefore, such changes and modifications may be made there- 30 from as do not affect the spirit of the invention nor exceed the scope thereof as expressed in the appended claims.

In the drawings:

Fig. 1 is a front elevation of the scanner.

35 Fig. 2 is a side elevation of the same.

Fig. 3 is a perspective view of the outer or stationary frame of the scanner.

Fig. 4 is a perspective view of the inner or movable frame of the scanner.

40 Fig. 5 is a perspective view of a mirror and its mounting.

Fig. 6 is a diagrammatic view of a source of oscillating current necessary in the television apparatus of my invention.

45 Fig. 7 is a diagrammatic drawing of a television system embodying my invention.

Figs. 8, 9, 10 and 11 are diagrammatic drawings of other television systems of my invention.

50 Fig. 12 is a diagrammatic drawing of a television system for viewing pictures stereoscopically.

Fig. 13 is a diagrammatic drawing of pick-up apparatus which may be employed in any of the 55 systems shown in Figs. 7 to 12, inclusive.

Fig. 14 is a diagrammatic drawing of an optical arrangement for the scanning system.

Fig. 15 is a view showing an embodiment of the 60 system shown in Fig. 14 and including means for adjusting the lens relative to the mirror.

Fig. 16 is a diagrammatic view of the scanning operation.

Fig. 17 is an elevational view showing a screen nonuniformly lighted, which is the effect obtained unless the screen shown in Fig. 19 or the 5 lens shown in Figs. 20 and 21 are used in the scanning system.

Fig. 18 is an elevational view of a uniformly lighted screen, the uniform lighting being obtained by the use of the apparatus of my invention. 10

Fig. 19 is an elevational view of a translucent sheet which may be interposed between the mirror and the screen of Fig. 16 in the position of the dotted line of said Fig. 16. 15

Fig. 20 is an elevational view of the concave face of a concavo-convex lens which may be used instead of the sheet shown in Fig. 19 in order to obtain a uniformly lighted screen.

Fig. 21 is a side elevation of the concavo-convex lens shown in Fig. 20; and 20

Fig. 22 is a diagrammatic drawing showing the lens of Figs. 20 and 21 in a scanning system.

Referring to the drawings for a more detailed description thereof and at first to Figs. 1 to 5, 25 inclusive, which show the construction of the scanner, the numeral 1 designates the static frame which may suitably be of soft iron and which serves as a support for an inner or floating frame 2. Frame 2 is vibratably supported by frame 1 30

by means of a pair of tense wires or strings 3 and the tightening mechanism 4 for said wires or strings. The lower wire 3 is secured to the bottoms of frames 1 and 2 while the upper wire 3 is secured to the top of frame 2 and to a strip 5 35

which is supported on screws 6a passing through the top of the frame 1. Nuts 6 and the heads of the bolts hold the strip 5 in position on the bolts while nuts 7 and 7a hold the bolts in adjusted position relative to the top of frame 1. The 40

adjustment of nuts 7 and 7a enable the tension of wires 3 to be adjusted as desired so that the desired period of vibration of frame 2 may be obtained. Notches 18 are made in the side edges 45

of the upper and lower portions of the frame 2 while notches 12 are formed in the side edges of strip 5 and the bottom member of frame 1 so that the wires 3 may be seated therein. The stationary frame 1 may be held in position by means of screws 8. Frame 1 carries the low frequency energizing coils 9, said coils having cores 10 of soft iron which are riveted or otherwise rigidly secured to frame 1 at points 11, as shown in Figs. 1 and 3. The coils 9 are connected in

series and are energized by the low frequency 50 oscillating current used for driving the device. The vibratable or low frequency frame 2, which also may be of soft iron, has two projections 13 extending from opposite side edges of the side members of the frame, these projections acting 55

60

as the armatures of the electro-magnets 9-10. Projecting inwardly of frame 2 from the top and bottom thereof are cores 14 and coils 16. The mentioned wires 3 pass through apertures 17 formed in the cores 14. The side or vertical members of frame 2 have apertures 19 to receive somewhat loosely screws 20 of the minor mounting. The screws 20 are held to the frame 2 by nuts in contact with the side or vertical members, as clearly shown in Fig. 1. The screws 20 pass through oblong pieces 22 and are held to said pieces by nuts 21. The pieces 22 are each perforated in two places to receive a wire loop 24, the plane of which is oblique to the side edges of the pieces 22. A vibratable armature 25 is secured to the loop 24 and carries a mirror 26. The armature 25 is the armature of the magnets 14-16. The coils 16 are connected in series and the oscillating current of higher frequency energizes them, thereby causing the armature 25 and the mirror 26 to vibrate at the higher rate of vibration. Furthermore as the armature 25 vibrates with the floating frame 2 at the lower frequency of vibration the mirror 26 will also vibrate at the lower frequency of vibration and hence will be acted on by two vibrating forces at right angles to each other, one vertical and the other horizontal. Since the rates of vibration are different, a beam of light reflected from the mirror will trace on a screen a Lissajoux figure of the zig-zagging type. Properly choosing the rates of vibration will cause the reflected beam to closely scan the television image. The air gaps between the cores 10 and the members 13 of the frame 2 and also the air gaps between the ends of armature 25 and cores 14 are so proportioned that no matter how great the amplitude of the vibrations may happen to be, neither the members 13 nor the armature 25 will come into contact with the cores 10 or 14.

Fig. 6 shows one means by which the scanner may be set into vibration. Two vacuum tubes 27 and 28 of the three element type have their filaments lighted from battery 29 and their plate currents supplied by battery 30, while their grid potentials are obtained from batteries 31 and 32, respectively. The plate and grid circuits of tube 27 are inductively connected to each other by means of transformer 33 as shown. The primary or plate coil of transformer 33 is connected in parallel with a condenser 34. The plate circuit of tube 27 and the grid circuit of tube 28 are inductively connected by means of transformer 35. From the plate circuit of tube 28, and in series with it, are the output binding posts. The oscillating circuit formed by the primary of transformer 33 and the condenser 34, is adjusted to the desired frequency; this causes the tube 27 to oscillate at that frequency. The oscillations are fed through transformer 35 into the grid circuit of tube 28, thereby causing the latter to oscillate at the same frequency, and hence the output will be an oscillating current of chosen frequency. Means may be provided for varying either the frequency of oscillation or the output of the oscillator. Three such means are shown in Fig. 6, namely, the condenser 34 may be partly or altogether variable, the rheostat 36 in the plate circuit of tube 27 may be used to reduce the plate current and to adjust the frequency of oscillation, the rheostat 37 may be used for changing the filament current of tube 37. Similar rheostats may be placed in the circuits of tube 28, as in the plate circuit, in series with or shunting the output, or in the filament circuit. These op-

tional means tend either to change the frequency, or the output, or both.

Figs. 7 and 8 show two methods for one-way television transmission and reception by wire. Two-way television may be accomplished using similar methods as shown in previous patents to the present inventor. Fig. 7 shows a suitable light source 38 energized either from a battery or electric mains. The light source emits a thin strong pencil of light 39, which is reflected by the scanner shown conventionally at 40 with the two driving coils 41 and 42. The reflected ray performs the scanning of the image 43 to be televised. The light reflected from the image is collected by suitable photo-electric cells 44. The photo-electric current is conducted by wires 45 to a suitable amplifier 46 which is energized from source 47. The amplified current is carried by line 48 towards the receiving station. The driving magnets of coils 40 and 41 are controlled by rheostats 49 and 50, respectively. The currents for energizing the coils 40 and 41 come from the oscillators 51 and 52, respectively, having a source 53 which may be local or from the electric means. The driving currents are carried towards the receiving station by pairs of wires 54 and 55.

The received photo-electric impulses are amplified at the receiving end by a suitable amplifier 56 having a source 57, and the amplified current is sent to energize a receiving lamp 30 (crater, neon or glow lamp) 58 and lens 59. The scanning device at the receiver has its driving magnets 60 and 61 controlled by rheostats 62 and 63, the energizing currents coming from the amplifiers 64 and 65 having sources 66, which amplifiers serve the purpose of amplifying the driving currents coming through the pairs of lines 54 and 55. The receiving lamp 58 sends a thin pencil of modulated light which is reflected by the scanner's mirror as ray 67, and goes to "scan" on a screen the received image 68.

With the system illustrated in Fig. 7 it will be necessary to use three pairs of wires, namely, 54 and 55 for synchronization and 48 for the photo-electric impulses. In Fig. 7, only two wires 45 are needed, namely, wires 69.

Fig. 8 shows a local source of light 70, scanner 71, image 72, ray of light 73, photo-electric cells 74, oscillators 75 and 76 with source 77, photo-current amplifier 78 with source 78a, and a pair of wires 69 which go to the receiving end. At the receiving end we have amplifier 79 and source 80, receiving lamp 81, scanner 82, modulated ray of light 83, received image 84, and two oscillators 85 and 86 with source 87, identical with those, 75 and 76, of the transmitter. The driving frequencies emanating from the oscillators are remarkably constant. Therefore, it is feasible to adjust the frequencies of 85 and 86 so that they be made identical with the frequencies of 75 and 76. In this manner, with simplicity and compactness, it is possible to televise using only one pair of wires, namely 69.

In Fig. 9, is shown another method by which television by one pair of wires may be accomplished. The numerals 88, 89 and 90 indicate respectively the pairs of wires carrying the two driving frequencies and the photo-electric currents. A suitable filter system 91 suppresses from the photo-electric impulses, those having the same frequencies as the driving currents. Then, the three currents are mixed in a modulator 92 with source 93, into one single current, the line current being sent by wires 94 to the receiving end. This line current consists of three com-

ponents: one of the lower driving frequency and of constant amplitude, another of the higher driving frequency and also of constant amplitude, and the photo-electric current with the preceding frequencies suppressed at filter 91. In practice it may be found that filter 91 is not necessary, since the suppressed frequencies of the photo-electric current may happen to be of constant amplitude and, therefore, there is no necessity of suppressing them. At the receiving end we have a general amplifier 95 with source 96. The amplified current divides into three branches as shown, one going to filter 97 which passes only one of the driving frequencies, another going to filter 98 which passes only the other driving frequency, and a third branch going to double-filter 99, identical with filter 91 of transmitter, intended to suppress the components of the driving frequencies. In this manner, the lines 100 and 101 carry the driving currents of the scanner, while the line 102 carries the energizing current of receiving lamp. In practice, as explained in relation with the transmitting end, the filter 99 might be found to be unnecessary.

In Fig. 10 is shown a similar method to that illustrated in Fig. 9 for transmission and reception of television images by radio. Conductors 88 and 89 carry the driving currents; conductors 90 carry the photo-electric pulses. 91 is a double filter (which may be unnecessary, as explained before) and 92 is the mixer or modulator. This modulator 92 modulates the oscillations (high frequency or radio-frequency) coming from the oscillator 103; the modulated frequencies act upon the radio-transmitter 104, and the issuing radio-waves or impulses go out to space by antenna 105 and ground 106. At the receiving end we have a receiving antenna and ground 107 and 108, respectively, a radio-receiver 109, with amplifier 110 and source 111. This amplifier 110 gives off three branches: one goes to filter 112, another to filter 113, and the third to filter 114; the use of these filters was explained under receiving end of Fig. 9. Lines 115, 116 and 117 serve the same purpose as lines 100, 101 and 102 of Fig. 9.

In Fig. 11 is shown another system for radio transmission and reception of television images. Lines 118 and 119 carry the driving currents of the transmitter's scanner; line 120 carries the photo-electric impulses; 121 and 122 are local sources for driving the scanner at the transmitter with source 123; 124 is a filter having the same purpose as filter 91 of Figs. 9 and 10; 125 is a modulator; 127 is a radio-frequency oscillator and 126 is the radio-transmitter. Filter 124 might be found in practice to be unnecessary. At the receiving end we have: receiving antenna 128; radio-receiver 129 and amplifier 130; local oscillators 131 and 132 for driving the scanner of the receiver in synchronism (due to characteristic constancy of oscillators) with the scanner at the transmitter; lines 133 and 134 carry the driving impulses for the scanner; and wires 135 carry the amplified photo-electric current to the receiving lamp.

In Figs. 12 and 13 are shown two television systems, one for transmitting stereoscopic or three-dimensional television images, and for receiving them; and another for daylight or direct television transmission.

Fig. 12 illustrates a system of stereoscopic television, 136 is the image to be transmitted; 137 is the scanning mirror; 138 is the source of light; 139 is one group of photoelectric cells; 140 is

another group, so placed with respect to 136 so as to receive light from another angle than group 139; 141 and 142 are the respective amplifiers for the currents from 139 and 140, respectively. Through 143 and 144 (which might be different radio carriers instead of wire lines as shown) the amplified currents are sent to the receiving end. At this end we have the scanning mirror 145 vibrating (by any of the means explained in previous systems) in synchronism with mirror 137 of the transmitter; receiving lamp 146 is energized (after suitable amplification) by current coming through 143, and receiving lamp 147 is energized (also after suitable amplification) by current coming from 144. Since the receiving lamps are placed with respect to the scanning mirror 145, as the photo-cells' groups 139 and 140 are placed with respect to the image 136, we will have two images, 148 and 149 formed on the receiving screen, each image depending on how each group of photo-electric cells 139 and 140 "sees" the transmitted image 136. Therefore, if a person places himself so as to look simultaneously through lenses 150 and 151, thus having the opaque diaphragm 152 vertically in front of his face as if dividing it into two equal halves, that person will see a different image with each eye, and if the placing of the photo-cells' groups 139 and 140 and of the receiving lamps 146 and 147 is properly arranged, the two images will blend in the person's brain and produce the impression to him that he is looking with both eyes to a single image, i. e. 136, and hence he will think he is looking at a three-dimensional figure. This is just like looking into an ordinary stereoscope. The only drawback of this method is the necessity of using two separate channels (either wire or radio, the first not being so great a drawback) for the transmission of the image. But it is to be remembered in this case that "zone television" also uses several channels for transmitting the complete image, one channel for each zone.

In Fig. 13 is shown an arrangement for securing daylight or direct television; that is to say, television not by the flying spot method, but television using the reflected light from the wholly illuminated image to be transmitted. Of course, this refers only to the transmitter. Referring to the Fig. 13, we have: The image to be transmitted, i. e., the image of object 153, is suitably illuminated, either by daylight or artificial light; a ray of light from any point of the image, as ray 154, for instance, will enter the dark-box 155, through the large aperture 156; this large aperture will, due to its size, permit rays from all points of the image 153 to enter simultaneously into the dark-box 155. The scanner 157 reflects those rays, as ray 158, towards the box (also dark) 159, which contains the photo-electric cell or cells 160. For zone television several cells are needed. Only a small beam, as 158, enters the dark-box 159 through an aperture 161. In case of zone television, as many apertures are needed as there are photo-electric cells inside the dark-box 159. Wires 162 carry the photo-electric impulses to the amplifier (which may also be placed inside the box 155); the wires 163 and 164 carry the energizing driving currents from the oscillators to the scanner 157. In this arrangement the scanning mirror of scanner 157 acts like the small aperture of a pin-hole camera; as the mirror vibrates, the rays coming from the image and reflected on it, are made also to swing back and forth and sideways, performing the operation of scanning with re-

spect to the aperture 161 on box 159. Therefore, each and every point of the reflected image is scanned successively by the photo-electric cell 160. In case of zone television, the vibrations of 5 157 are so arranged as to permit that each aperture as 161 will scan only a zone of the image. A separate cell and amplifier and channel is required for each zone. The aperture 156 is shown without any additional optical system; it may be 10 provided with an optical system in order to shorten the distance between 156 and the scanner 157, if desired, or to permit changing the focus of the image to be transmitted, so as to permit close-ups or far away scenes. Also, the aperture 156 may be provided with small lens and dia- 15 phragm (of the iris type used in photography), so as to permit adjusting the size of the scanning beams going into the photo-electric cell, thus modifying at will the degree of detail obtainable 20 from the illuminated image 153. The photo-cell amplifier and the oscillators for driving the scanner may be arranged inside the box 155 if preferred, only by increasing the size of said box. Box 155 and box 159 are blackened boxes to avoid 25 spurious and undesirable stray light from getting into the cell and spoiling the transmission.

The direct type of television transmitter shown is suitable for television of motion pictures, by 30 simply projecting the motion picture on a screen at 153 (Fig. 13), the reflected light from this screen being used for the scanning. In this manner, television transmission of a motion picture may be accomplished from a theatre without the necessity of "passing" the picture expressly for 35 the television transmission; the scanner in this case serves the purpose of the "eyes" of a large audience; in other words, the television transmitter-scanner "seats" itself within the audience as any one of the audience. In this manner, it 40 is also suitable for transmitting scenes from the stage or in the fields of sport, etc. The scanner just takes the place of a spectator.

According to my invention I may place in the path of the scanning beam an optical system 45 adapted to enlarge the scanning rectangle and/or modify the motion of the scanning beam. Two means are hereinafter described, by which this may be accomplished. Having in mind the fact that the scanner herein shown and described has 50 almost simple harmonic motion, in Fig. 16, 165 is the scanning beam from the light source, 166 is the scanning mirror and 167 is the screen or object. Without any optical system between the mirror and the screen or object 167, the image 55 (scanning rectangle) produced on said object or screen 167 is of the type shown in 168, where we can see that the light appears to the eye (due to persistence of vision) as accumulated towards the sides and corners of the scanning rectangle. 60 This "crowding" of the light towards the sides and corners (principally towards the latter) is due to the character of the motion of the scanning beam, which, as said before, is almost simple harmonic motion. This "crowding" of light is not 65 desirable; my improvements eliminate this. One of the "crowding eliminators" is a photographic film or plate, and the other is a special lens or combination of lenses.

The desired effect is shown in Fig. 18, i. e., a 70 uniformly illuminated area. If in the path of the scanning beam (Fig. 16) is interposed at the dotted place marked 169, a photographic film or plate, and the scanning process effected over its active surface for the sufficient length of time 75 (a fraction of a second probably, this time de-

pending on the light flux used), the scanning rectangle will be photographed on the film or plate. After developing and fixing, the transparent film or plate will look something like Fig. 19, with the points on the rectangle which appear with more light to the eye, appearing blacker in the film or plate. Now, if the film or plate is again placed at 169, it will absorb light at the places we desire to have it absorbed, and the scanning rectangle produced at 167 will be like 10 170. This, then, is a way of eliminating the crowding of light. The film or plate may be used in place of screen 167, thereby serving as the receiving screen. An opaque screen of non-uniform reflecting power will serve the same end. 15

The other means proposed is the use of a lens or system of lenses, which will enlarge the rectangle and at the same time eliminate the "crowding". The rectangle enlargement may be then decreased and brought to the desired size 20 (if this is necessary) by means of proper lenses in the ordinary way.

Figs. 20 and 21 illustrate a suitable form of lens for eliminating the "crowding", at the same time enlarging somewhat the size of the scanning 25 rectangle. The lens illustrated is of the concavo-convex type, the concave side being spherical and centered at the scanning mirror, so as to have the beam of light pass without deviation to the convex side; in other words, the 30 scanning beam will enter the concave side of the lens normally. The convex side of the lens is of such a shape (calculable mathematically) as to produce the desired "uncrowding" of the light; in other words, the surface 172 deviates the 35 scanning beam in such a manner as to convert its almost simple harmonic angular motion into an almost straight (or direct proportion) angular motion. It is impossible (also demonstrable mathematically) to absolutely transform the 40 simple harmonic motion into a straight line (reversing, back and forth) motion, in this manner, but an approximate solution is practical.

To illustrate more clearly the object of the lens, refer to Fig. 22. 172a is the scanning beam 45 from the source of light; 173 is the scanning mirror which is supposed to be vibrating in this case in only one direction, namely, about horizontal axis (this is for clearness in the description); 174 and 175 are the maximum deviations experienced by the scanning beam as reflected from the vibrating mirror; 176 is the lens under question (we see that the beam follows its direction without deviation up to the convex side of the lens); at the convex side of the lens, the beam 174 is 50 deflected to 177 and the beam 175 to 178; 182-183 is the receiving screen or subject being televised; if the lens had not been interposed in the path of the beam of light the "scanning line" would take place at 184-185 on the screen or 55 subject; 184-185 is smaller than 182-183, of course. The image "line" produced without the lens would appear as 181; with the lens introduced, the image "line" would appear uniformly (almost) illuminated as in 186. Of course, the 60 other motion of the mirror would produce the other component of the scanning "rectangle" which would, consequently, appear almost uniformly illuminated.

It is to be noted that the convex surface 172 of 70 the lens must have a curvature smaller than the concave surface has, so as to permit the enlarging of the "scanning rectangle". This makes the lens thicker at the edges than at the center.

Referring again to Fig. 16, it is also to be noted 75

that if it be required to enlarge the "scanning rectangle", it is only necessary to place a suitable lens between the film or plate at 169 and the screen or subject 161. This lens must be also 5 thicker at the edges than at the center to avoid reversal of the scanning, which would happen in case a double-convex lens were used.

Optical system of the apparatus

10 Figures 14 and 15 illustrate an optical system for the apparatus, whose object is to reduce the size of the device. Fig. 14 shows it diagrammatically: 187 is the scanning device; 188 is the vibrating mirror of same; 189 is the source of 15 light, either of the transmitter or of the receiver; 190 is the condensing lens for concentrating the image of the source 189 onto the subject or receiving screen at 192; 191 is a reflecting surface (mirror). The light from 189 is concentrated 20 by 190, reflected by 191, reflected again by 188 and at 192 is formed the image of source 189.

Fig. 15 shows the practical arrangement: 189 is the source of light, which is an incandescent filament (inside of a gladd bulb not shown) at 25 the transmitter, and the crater of a regular crater type of television lamp at the receiver. In the first case, 189 is not modulated, while in the second case, 189 is modulated proportionately to the photo-electric cells' impulses duly amplified and 30 received either by wire or radio (regular routine). In other words, 189 is the source of light of the device, 190 is the condensing lens; 191 is the reflecting mirror; 193 is the enclosing case; 194 is the focusing device for lens 190 in telescoping 35 tube 195; the mirror 191 is pivoted about axis 196; case 193 has a projecting part 197 which serves the good purpose of screening off stray light which could otherwise go to the subject or screen.

40 The mirror 191 is pivotally mounted at 196 (Fig. 15) so that it can be tilted at the proper angle and send the beam of light towards the vibrating mirror as shown in Fig. 14. The device shown in Fig. 15 may have its longitudinal axis 45 (which passes through source 189 and center of lens 190) either vertical or at any other suitable angle.

What is claimed is:

1. A pickup camera for television or facsimile 50 comprising a closure, an opening in said closure for viewing therethrough an externally positioned image from within said closure, a single, two direction vibrated, mirror scanner positioned in said closure in line with said opening and said 55 externally positioned image, and angularly facing said opening, and a photo-electric cell located within said closure in a position within the field of reflection of said mirror scanner, and out of line of view between said mirror scanner and said 60 said image.

2. A pickup camera for television or facsimile comprising a closure, an optically treated opening in said closure for viewing therethrough an externally positioned image from within said 65 closure, a single, two direction vibrated, mirror scanner positioned in said closure in line with said optically treated opening and said externally positioned image, and angularly facing said optically treated opening, and a photo-electric cell 70 located within said closure in a position within the field of reflection of said mirror, and out of

the line of view between said mirror scanner and said image.

3. A pickup camera for television or facsimile comprising a closure, an opening in said closure for viewing therethrough an externally positioned image from within said closure, a single, differently vibrated as to period in each of two directions, mirror scanner positioned in said closure in line with said opening and said externally positioned image, and angularly facing said 10 opening, and a photo-electric cell located within said closure in a position within the field of reflection of said mirror scanner, and out of the line of view between said scanner mirror and said image. 15

4. A pickup camera for television or facsimile comprising a closure, an opening in said closure for viewing therethrough an externally positioned image from within said closure, a single scanner mirror suspended to dually vibrate in right angle 20 directions at selected different periods suitable for scanning purposes positioned in said closure in line with said opening and said externally positioned image, and angularly facing said opening, and a photo-electric cell located within said 25 closure in a position within the field of reflection of said mirror scanner, and out of the line of view between said scanner and said image.

5. A pickup camera for television or facsimile comprising a closure, an opening in said closure 30 for viewing therethrough an externally positioned image from within said closure, a single, two direction vibrated, mirror scanner positioned in said closure in line with said opening and said externally positioned image, and angularly facing 35 said image and opening, and a photo-electric cell located within a second closure within said first mentioned closure in a position within the field of reflection of said mirror, said second closure having an aperture therein located on 40 a line between said mirror and said photo-electric cell.

6. A pickup camera for television or facsimile comprising a closure, an opening in said closure for viewing therethrough an externally positioned image from within said closure, a single, two direction vibrated, mirror scanner positioned in said closure in line with said opening and said externally positioned image, and angularly facing 45 said image and opening, a second closure 50 located within said first mentioned closure, a photo-electric cell located within said second closure in a position within the field of reflection of said mirror, and an optically treated aperture in said second closure located on a line between 55 said mirror and said photo-electric cell.

7. A pickup camera system for television or facsimile of the type claimed in claim 1, characterized by the light path between the image and the mirror scanner including an optical system. 60

8. A pickup camera system for television or facsimile of the type claimed in claim 1, characterized by the light path between the photo-electric cell and the mirror scanner including an optical system. 65

9. A pickup camera system for television or facsimile composed of two or more associated, simultaneously operable, cameras, each characterized by the structure set forth in claim 1. 70
